UNITED STATES PATENT OFFICE

EMANUEL PAPPERT, OF NEW YORK, N. Y.

DESIGN FOR AN OPTICAL FRAME

Application filed June 21, 1929. Serial No. 31,788. Term of patent 7 years.

To all whom it may concern:

Be it known that I, EMANUEL PAPPERT, a citizen of the United States, residing at the city and State of New York, county of Bronx, have invented a new, original, and ornamental Design for an Optical Frame, of which the following is a specification, reference being had to the accompanying drawing, forming part thereof.

Fig. 1 is a front view of an optical frame, showing my new design, a series of perforations being provided at the upper member of the bridge.

Fig. 2 is a top plan view of the same. Fig. 3 is an enlarged view of the engraving on the lens frame, it being understood that the ornamentation extends over the entire front and top of the lens frames, as indicated.

Fig. 4 is a perspective view on an enlarged scale of a portion of the upper part of the bridge.

I claim:

The ornamental design for an optical frame as shown and described.

EMANUEL PAPPERT.
